UNITED STATES PATENT OFFICE.

JAMES I. AYER, OF CAMBRIDGE, MASSACHUSETTS, ASSIGNOR TO SIMPLEX ELECTRIC HEATING COMPANY, OF CAMBRIDGE, MASSACHUSETTS, A CORPORATION OF MASSACHUSETTS.

ELECTRICALLY-HEATED CULINARY APPARATUS.

1,120,884.

Specification of Letters Patent Patented Dec. 15, 1914.

Application filed December 2, 1912. Serial No. 724,493.

To all whom it may concern:

Be it known that I, JAMES I. AYER, a citizen of the United States, and resident of Cambridge, county of Middlesex, State of Massachusetts, have invented an Improvement in Electrically-Heated Culinary Apparatus, of which the following description, in connection with the accompanying drawings, is a specification, like letters on the drawings representing like parts.

My invention relates primarily to a provision for securing the most direct and efficient transmission of heat from the heating device to the article heated without requiring a special clamping arrangement or attachment between the bottom of the culinary utensils and the top or edges of the heater. In many instances, as for instance in connection with relatively large vessels or expensive vessels, such as chafing dishes, for example, it is impracticable or at least not advisable to provide the usual clamping ring or device on the bottom of the dish or utensil, and also in many instances I have found that better heating results may be secured by applying clamping pressure throughout the entire area of the utensil, as, for instance, by applying the downward pressure directly over the upper edge of the vessel.

For securing proper heating it is necessary to hold the vessel in intimate contact with the electric stove, and the previous ways of accomplishing this have been usually to form an engagement between the bottom of the vessel and a clamp attached to the heater or an engagement between a projection of the bottom of the vessel and the heater, and my invention aims to secure the same desired results of increased efficiency and with intimate contact with the heater with vessels that will not permit of arranging the clamp to engage with the bottom of the vessel.

To this end my invention resides in providing, in connection with the stand or heater, means for holding the entire vessel under pressure by applying clamping or pressure-applying means at the side and above the bottom or in direct engagement with the top edge or opening of the vessel.

By this invention I obviate the expensive and in many respects objectionable spur rings, clips, turned grooves, and other forms at or near the bottom of the vessel, and I

leave the bottom of the vessel smooth and free from these grooves and protuberances which collect dirt and render cleaning difficult.

The constructional features and further details of my invention will be pointed out more at length in the course of the following description, taken in connection with the accompanying drawings, in which I have shown several preferred embodiments of the invention.

In the drawings, Figure 1 is a view in side elevation, partly broken away, showing one form of my invention; Fig. 2 is an enlarged longitudinal sectional view of the movable member of the clamp; Fig. 3 is a fragmentary cross sectional view taken at right angles to the section of Fig. 2; Fig. 4 is a top plan view of the parts shown in Fig. 1; Fig. 5 is a view similar to Fig. 1 of another embodiment of the invention; Fig. 6 is a fragmentary top plan view of the movable member of the clamp of Fig. 5; Fig. 7 is a fragmentary view in side elevation of a third form of my invention; Fig. 8 is a top plan view of the heater stand and frame; Fig. 9 is a view in side elevation of another embodiment of my invention; Fig. 10 is a similar view, partly in section, of still another embodiment of my invention; Fig. 11 is an enlarged, broken perspective view of the frame rim shown in Fig. 10; and Figs. 12 and 13 are views similar to Figs. 10 and 11 respectively of still another form of the invention.

The heater 1 and its supporting stand or legs 2 may be of any usual or preferred kind providing a proper resistance medium 3 and flat top heating plate 4 on which the vessel to be heated may be pressed hard down for securing the desired increased efficiency of heat conduction. Projecting upwardly from the stand I provide a frame comprising a series of legs 5 preferably three in number, and as shown in Fig. 1 a receiving ring 6 rigidly mounted at the upper end of these, of sufficient size to receive the chafing dish or other utensil which is to be heated by being clamped hard down upon the plate 4.

As shown in Figs. 1-4 this frame is provided with a pair of hook shaped fingers or fixed jaws 7 having their curved upper ends or jaws at the exact height to hold or

wedge the dish hard down against the heating plate when the edge of the dish is caught thereunder. Preferably these jaws 7 are at a vertical distance from the plate 4 very slightly less than the normal height of the rim 8 of the chafing dish or other vessel 9 which is to be heated so that when the dish is tipped very slightly so as to bring its edge 8 under these clips and then has its opposite side pressed down level, the jaws or clips 7 will tend to wedge or press the side of the chafing dish or vessel 9 hard down in direct intimate pressing engagement with the heating plate 4. At the opposite side of the frame, and as herein shown, at the upper end of the third leg 5 I secure to the ring 6 a movable clamp shown as a lateral or horizontal plate or bracket 10 within which slides the foot 11 of a clamping device, whose exposed outer end 12 is bent to constitute a clamping and wedging hook 13 as best shown in Figs. 1 and 2, said clamping device having a transverse slot 14 formed in its outer end to receive the reduced lower end 15 of a screw stud 16 mounted eccentrically in a rotary actuator 17 provided with a handle 18. Thus when the handle 18 is turned around to the right from the position shown in the drawings, it instantly moves the clamp 12 forward into hard pressing engagement with the rim 8 of the vessel 9 coöperating with the clips 7 to hold said vessel in the desired intimate contact with the heater.

In the construction shown in Figs. 5 and 6 I have shown the same frame and clips 7, but instead of the hoisting clamp 12 I have provided a somewhat stronger construction for coarser work, consisting of a bracket 19 on which is pivoted at 20 a clamp 21 having a rearwardly extending handle 22 normally held upward by a coiled spring 23 whose pressure tends constantly to hold the clamp 21 in continuous pressing engagement with the rim 8 of the vessel being heated.

In Figs. 7 and 8 I have shown the frame as having a top ring 24 provided in its edge with downwardly and laterally extending slots 25 like a bayonet joint, two of said slots being herein shown at diametrically opposite points of the ring 24, these slots both extending lengthwise of the ring in the same circumferential direction to coöperate with short studs or pins 26 preferably extending out from the base of the adjacent handles 27 which are secured at or adjacent the rim 28 of utensil 29 being heated.

In Fig. 9 I have shown a still simpler form of my invention consisting of spring extensions 30 having hook shaped upper ends 31 which, when the dish 9 is simply forced down between the spring extensions 30 onto the heating plate 4, snap over the rim 8 of the dish and thereby hold the latter firmly down upon the heater, the spring

lugs or brackets 2 greatly facilitating this movement.

In Figs. 10-13 I have shown a heavier and stronger clamping construction. A relatively heavy ring 32 angular in cross section, as best shown in Fig. 11, is shown as constituting the top ring of the supporting frame or stand, this ring in Figs. 10 and 11 being shown as provided with radial slots 33 in its top horizontal or in-turned edge 75 and an adjacent undercut or oblique portion 34 for coöperating with pins 35 projecting from the vessel 36 close to the upper part and preferably immediately adjacent the rim 37. Thus, when the dish 36 is put 80 in place on the heater plate 4 with its pins or lugs 35 dropped through the slots 33 in the ring 32, it may be tightened against the plate 4 with such intimate contact and hard pressure as the user may desire, simply by 85 turning the dish more or less around to the left, Fig. 11, so as to compel the pins 35 to slide hard against the downwardly inclined ledge 34 and thereby wedge the dish or utensil 36 downward with the desired pressure. 90 In Figs. 12 and 13 a still further construction is shown in which a ring 38 being U-shaped in cross section constitutes the top ring of the supporting frame, having slots 39 the same as the slots 33 in Fig. 11 and an 95 adjacent inclined surface 40 for substantially the same wedging action as before, and coöperating with this ring are outwardly bent ears or lugs 41 on the lower ends of the relatively heavy handle brackets 100 42 whose handles 43 are shown as projecting upwardly above the rim of the vessel 44. This construction is well adapted to relatively heavy and large vessels. The vessel is grasped by the two handles and set 10 down within the ring 38 so as to permit the lugs 41 to pass through the slots or openings 39 in said ring and is then given a strong twist in the proper direction to bring said lugs into wedging engagement beneath 11 the inclined flange or wedging surface 40 of the frame ring, the result being that the vessel is wedged hard down in properly clamped relation to the heater on the heater stand.

From the foregoing description it will be understood that in each instance the vessel is clamped by pressure applied at or adjacent its rim or upper edge and transmitted downwardly through the sides of the entire 12 vessel, this clamping action being resisted by the clamping frame and thereby transmitted to the heating plate or stove top to which said frame is rigidly secured. By this means the efficiency of the electric 12 heater is increased without requiring any special formation of the heating plate on the one hand, or of the bottom of the vessel or dish on the other hand, leaving the said bottom smooth and entirely without 13

ears, pins, rings, or other projections, grooves or conformations which have heretofore been considered necessary and have been liable to accumulate dirt and render their cleaning difficult and their use objectionable.

By the means constituting my invention the vessel is held in firm contact with the surface of the electric heater by being 10 clamped by holding devices arranged to engage either the top or sides of the pan or dish as distinguished from clamping or locking devices engaging the bottom or lower sides of the vessel at the bottom.

15 My invention is capable of a wide variety of embodiments as evidenced by the several illustrative examples herein set forth.

Having described my invention, what I claim as new and desire to secure by Letters 20 Patent is:

1. The combination with an electric heater for receiving a vessel to be heated, of clamping means comprising a frame rigidly connected with the heater and provided at a 25 plurality of points with engaging devices to coöperate with the top rim of the vessel, a movable clamping member carried by said frame adapted to coöperate with the top of

the vessel and exert a downward clamping pressure thereon. 30

2. The combination with an electric heater for receiving a vessel to be heated, of a clamping device comprising a frame rigidly connected with said heater and provided with means for engaging the vessel at a plurality of peripheral points near the top of the vessel with a downward clamping pressure, at least one of said means coöoperating with the vessel to give a downward wedging action. 35

3. The combination with an electric heater for receiving a vessel to be heated, of clamping means for engaging said vessel near the top and maintaining the vessel clamped in intimate contact with the heater, including 40 a receiving ring rigidly connected to the heater comprising an inturned flange and provided with a plurality of engaging devices. 45

In testimony whereof, I have signed my 50 name to this specification, in the presence of two subscribing witnesses.

JAMES I. AYER.
